FREEZING APPARATUS

John F. Furry, Galesburg, and Arthur D. Ames,
Lake Bracken, Ill., assignors to Outboard, Ma-
rine and Manufacturing Company, Waukegan,
Ill., a corporation of Delaware

Application April 15, 1939, Serial No. 268,042

12 Claims. (Cl. 62—126)

This invention pertains to refrigerating apparatus of that type which utilizes a freezing chamber in association with an evaporator coil.

Objects of our invention are, to provide:

An evaporator having a double tube or counter-flow-coil arranged and adapted to equalize the temperature throughout the freezing chamber, delay the accumulation of excessive frost upon the colder portions of the tube and prevent defrosting of other portions of the tube during off-cycle periods:

An evaporator of the coiled tube type with means for trapping liquid refrigerant in the upper portion of the coil in such a manner as to permit the flow of gas through the coil, and to prevent defrosting of the upper coil surface during off-cycle periods such as would otherwise result from the natural drainage of liquid from the upper to the lower portions of the coil:

An improved freezing chamber as a part of the evaporating unit, in which a transparent or translucent filter wall permits illumination while excluding the heat carrying rays emanating from the source of light, and confining the admitted light to the cold rays from the blue-green end of the spectrum:

Means for checking the heat flow to a directly refrigerated portion of an evaporator chamber from a portion thereof not directly refrigerated, whereby to prevent frosting of the indirectly refrigerated portion, when relatively warm moisture carrying air comes in contact therewith; and to provide a freezing chamber housing which is easily removable from its supporting base for the purpose of cleaning both the housing and the evaporator coil or associated parts.

Further objects are to provide:

A combination with the walls of a chilling unit of conduit members spaced from such walls and provided with liquid holding traps in their upper portions, whereby a flow of cold air may be maintained over the walls during off-cycle periods, partly by direct refrigeration due to evaporation of the trapped liquid, and partly by air circulation around the frosted conduits.

Means for preventing descending air, chilled by contact with the upper conduit portions, from intermixing with warmer air until it has passed below the side walls of the chilling unit.

In the drawings:

Figure 1 is a side elevation, partly in vertical section, of our improved evaporator.

Figure 2 is a plan view of the evaporator, partially in section.

Figure 3 is a front view of our evaporator with parts broken away.

Figure 4 is a view in perspective of the removable portion of our freezing chamber housing.

5 Figure 5 is a fragmentary view in partial section of the upper portion of one coil convolution disclosing the means of trapping liquid refrigerant therein.

Figure 6 is a fragmentary plan view in partial 10 section of the front bottom portion of our evaporator, showing our heat check and associated portions of the coil.

Figure 7 is a view similar to Figure 5, showing a modified form of entrapping liquid refrigerant.

15 Like parts are identified by the same reference characters throughout the several views.

In Figures 1 and 2, our improved evaporator unit is shown as we prefer to mount it in a household refrigerator of conventional type. Our improved unit includes a conduit, preferably a feeder pipe and a tubular coil which has disposed within the convolutions thereof a base plate 11, on which is removably mounted a housing 12 having a door 13 secured to the front thereof by means of hinges 14. The housing 12 has a light filter end plate or rear wall 15, hereinafter more particularly described. This wall may be directly connected with hangers 16 by bolts 17 and 17', which also serve to connect the filter wall 15 with upturned flanges of the housing base 11 and the shelf 20, respectively. The hangers 16 are elbowed at their upper ends and clamped to the top 21 of the liner wall of the food storage chamber by clamping bolts 22. Shelf 20 is used to support trays for ice cubes or other material to be frozen. Its front end is supported by brackets 24 which are welded to the base plate 11 and to the shelf 20 at their respective ends.

The evaporator is adapted to be employed in a 40 refrigerator circuit having the conventional high-side and low-side refrigerant areas. A conventional expansion valve 33 is employed to periodically permit a regulated flow of refrigerant from the high-side to the low-side. Our improved 45 evaporator is, of course, placed in the low-side and our feeder tube 31 is directly fed from the expansion valve.

Our improved evaporator conduit includes a 50 feeder tube 31, an outflow coiled tube 27, and a return or inflow tube 29. As shown in Figures 1 and 2, the feeder tube 31 extends from the expansion valve 33 upwardly along the rear side of the end plate 15, and then through the end plate underneath the shelf 20 in a series of laterally 55 extending loops leading to the front end of the

shelf, and then back along one side and through the plate 15. It then extends downwardly and is connected to the receiving end of the coil 27.

As shown in Figures 2 and 6, the coiled portion of the conduit is of double-tube counterflow construction, and while in effect it is a continuous conduit, yet, for the purpose of distinction, coil 27 may be called the outflow coil and coil 29 the inflow or return coil. The coils are wound either in the form of a helix or its functional equivalent in which the bottom portions of the convolutions extend obliquely toward the front end of the unit, and the other portions of the coil are in a plane normal to the axis of the unit. At the front portion of the unit, the coils are interconnected by means of a U-tube 30.

The tube 29 follows the convolutions of the tube 27 from the front to the rear end of the unit and the two tubes are soldered or otherwise secured together to provide rigidity by mutual reenforcement and to permit heat transfer from one tube to the other, whereby the temperature within the two tubes tends to equalize.

The feeder tube 31 may be fixedly secured to the under surface of the shelf 20, whereby the shelf supports the looped portion of the tube. The tubes 27 and 29 are of larger interior diameter than the tube 31, and therefore permit of a more rapid expansion in the coiled portions of the conduit which encircle the chilling unit. Also, due to the fact that the tubes 27 and 29 are connected by solder or other heat transferring material, the temperature of the return or inflow tube 29 is kept substantially equal to that of the outflow tube 27.

During the off-cycle periods, ordinary evaporator coils contain liquid only in the bottom portions of the convolutions since the liquid drains from the upper portion to the lower portion as soon as the circulating force ceases. To offset this, we provide means for trapping quantities of liquid in portions of the convolutions above the bottom. In Figure 5, this is accomplished by depressing the top portion of the convolution, or at least the bottom wall thereof, sufficiently to retain a quantity of liquid subject to evaporation during the off-cycle period. From a functional standpoint, it is not material how these traps are formed or whether they are formed wholly in the top portions or partially in the vertical portions and it is immaterial whether they are provided by deforming the wall of the tube or by attaching cup-shaped pocket members 49 as shown in Figure 7.

Defrosting of the upper coil portion is thus retarded by continuing vaporization until all of the entrapped liquid has evaporated. This tends to equalize the temperature in the top and bottom coil portions during off-cycle periods, since vaporization is proceeding both at the top and bottom of the coil.

As shown in Figure 1, the obliquely positioned bottom portions of the convolutions of coils 27 and 29 are soldered or otherwise secured to base plate 11. By this means the side and top portions of the paired convolutions are mutually supported, with the pairs in spaced relation to each other and to the chamber 12.

Spacing refrigerating coils from the housing of a chilling unit is not novel per se, but in our improved structure, wherein liquid refrigerant is trapped in the top portions of the coils, we invoke a new principle of operation, in which the spacing of the coils acquires added importance. The trapped refrigerant not only prevents defrosting

of the tops of the coils during the off-cycle period, but maintains a body of frost out of contact with the housing, so that air circulates downwardly over the frosted surfaces and flows along the top of the housing and down the sides thereof. In this manner we positively limit, or at least delay, the rise of temperature in the housing wall until the supply of trapped liquid is exhausted, and for a considerable period of time thereafter, because of the air currents circulating around the top portions of the coils and flowing downwardly over the surfaces of the housing. This tends to maintain a body of frost on the tubes of a more nearly constant thickness than has heretofore been possible. It prevents the accumulation from becoming sufficient to contact with the housing and shut off circulation of air around the tubes. This advantage is in addition to the function of the trap in prolonging the period of low temperature during the off-cycle period, and in preventing a complete defrosting of the top of the coil.

The vertical, or side portions of the convolutions may be not only spaced from the housing, but shields 50 may be interposed. Therefore, if these portions defrost during the off-cycle period relatively warm air which might otherwise pass between them, will be excluded from the cold currents flowing downwardly from the top portions within which liquid is trapped for continued refrigeration.

The shields 50 may have portions offset between the paired coils to interlock them with the coils and render them self-supporting.

A rectangular frame comprising the rod 38, which is preferably of plated solid material, is secured to base plate 11 near the front margin thereof for the purpose of adding an attractive appearance to the freezing unit. Its horizontally extending top portion is secured to the lower end 37' of the hanger 37. Said hanger portion 37' is also secured to the convolutions of the evaporating coil.

A control unit 36, including a mounting plate 35, may be secured between the hangers 37. The front margin of base plate 11 is flanged downwardly, as shown at 40, Figure 3, and its side margins are flanged upwardly as shown at 41, Figure 1, to provide mounting and sealing means for housing 12, which, together with base plate 11, form the side walls of the freezing chamber. Housing 12 has all of its margins flanged inwardly. When the housing is in place, the flanged rear end walls are in sealing contact with plate 15, as shown at 32, Figures 1 and 2. The side wall bottom marginal flanges are fitted with gaskets of rubber or the like, as best shown at 43, Figure 4, to provide a seal between the housing and the base plate. The front end marginal flanges are provided with a continuous gasket 44, Figure 4, to provide sealing means between the housing and the door 13.

Door 13 is a metal framed glass door, identical, in construction to the evaporator unit door described in Limpert Patent 2,158,877 and we therefore do not separately claim the door as a part of this invention.

We provide a transversely extending slot 45 near the front margin of the base plate 11, and we anchor therein, in lapping engagement with the walls of said slot, a strip 46 of non-heat conducting material such as rubber, for the purpose of retarding heat transfer from the front margin of the plate to the refrigerated portion at the rear of the slot. By the provision of this strip, we prevent the front portion of the unit,

including the door, from becoming as cold as the remainder of the unit, and it does not frost over upon successive opening and closing of the refrigerator door.

The interior of the freezing chamber is illuminated by means of either direct or reflected light from a source within the refrigerator, which is preferably controlled to function only when the refrigerator door is open. We prefer to locate the source of light behind the evaporator unit in a position to directly illuminate the interior of the freezing chamber as by bulb 55 and hence illuminate indirectly a portion of the refrigerator interior. Filter plate 15 may be of a transparent colored material, such as glass, or of a translucent colored material, such as Celluloid, but we prefer to use one of the colored plastics which are now commercially available.

Blue colored plastic provides an efficient filter for the red and infra-red rays, thereby excluding both the undesired color and heat which would otherwise enter the freezing chamber. Plastic of this type is infrangible, and hence will not break when struck by the ice cube trays. We have found that by the use of a blue plastic, the interior of the freezing chamber may be sufficiently illuminated, and the resultant cold blue light does not appreciably heat the interior of the freezing chamber despite the close proximity of the lamp thereto.

We claim:

1. In a refrigerator, an evaporator having a source of artificial light adjacent thereof, said evaporator having a heat insulating chamber with a wall portion adapted to admit cold light rays of the blue-green end of the spectrum into the chamber and to exclude the warm light rays of the red and infra-red portions of the spectrum therefrom.

2. In a chilling unit provided with a door, a heat conducting wall having one portion adjacent the door and transversely slotted to separate the portion adjacent the door from the portion remote therefrom, and a strip of non-heat conducting material disposed in said slot to resist heat conduction from the portion adjacent the door to said remote portion.

3. The combination with the walls of a chilling unit having a linear heat conducting surface provided with a slot, of a strip of non-heat conducting material disposed within the slot and biased therein in pressure engagement with the margins of the slot whereby to retard heat transfer between portions of said wall separated by the slot.

4. In an evaporator, a metallic freezing chamber having a door and a heat conducting base provided with an elongated transverse slot adjacent the door, a strip of heat insulating material filling the slot and adapted to check the flow of heat from the vicinity of the door to the base portion separated therefrom by said slot.

5. In a refrigerating apparatus, a freezing chamber and an adjacent source of artificial light, said chamber including the combination of a base, a removable elongated housing of U-shaped transverse section, an interior shelf supported and spaced from said base, a refrigerant conducting conduit encircling and spaced from the sides and top of the freezing chamber and 70 having its bottom portion rigidly secured to the base to permit heat transfer between the conduit

and the base, and a rear wall enclosing the end of said housing and adapted to admit rays of said artificial light from the blue-green end of the spectrum while excluding heat rays.

5 6. A chilling unit including a housing, a conduit encircling the housing and comprising an outflow tube section and an inflow tube section in free communication and unitarily connected for heat exchange in counterflow relation substantially throughout their extent, the unitarily connected sections comprising said conduit being disposed in coils about the housing having mutually spaced convolutions.

10 7. A device as set forth in claim 6, having top portions of the conduit depressed to trap liquid therein, whereby to maintain evaporation in both the upper and lower portions of the coils during operation of the unit in an appropriate refrigeration circuit after the supply of liquid to the unit 20 has been cut off.

25 8. An evaporator comprising an outflow tube section and an inflow tube section directly coupled at one end for unimpeded flow of refrigerant through one conduit and back through the other, said tube sections having portions 30 mutually joined for heat conduction therebetween, the joined portions of said sections extending along a general helical path throughout their extent to comprise mutually spaced convolutions of paired tubes.

35 9. In a refrigerator, an evaporator having a walled freezing chamber, said chamber wall including a portion of light filtering and heat excluding material adapted to admit the blue-green portion of the light spectrum, and a source of light exterior of the evaporator for the illumination of the chamber interior by light passing through said walled portion.

40 10. A refrigerator including a freezing unit having a chamber provided with a wall of light-transmitting material adapted to exclude at least some heat, and a source of light exterior to said freezing unit and proximate to said unit wall, whereby light from said source penetrates the 45 wall into the chamber to enable the user to view the interior of the freezing chamber.

45 11. In a refrigerator, a freezing unit comprising a substantially closed chamber having top, side, bottom and rear walls at least one of which 50 comprises heat excluding, light transmitting material, and a door comprising transparent material; an evaporator associated with said chamber for withdrawing heat therefrom, and a light exteriorly proximate to said light transmitting 55 material for illuminating the contents of the chamber and rendering them visible through the door without unduly heating them.

60 12. An evaporator including an open ended housing generally rectangular in cross section and disposed in a horizontal plane, and a continuous conduit encircling said housing to extend substantially the length thereof and having side and top portions spaced therefrom, said conduit comprising an outflow tube section and an inflow tube section in free communication and unitarily 65 associated for heat exchange in counterflow relation substantially throughout their extent, the unitarily associated sections being disposed in mutually spaced convolutions about said housing.
